CONDIMENT CONTAINER

Sydney E. Bender, 1455 Jasmine St., and Lenore B. Donnelly, 1900 Iris St., both of Denver, Colo.

Filed Mar. 7, 1960, Ser. No. 59,636

Term of patent 14 years

(Cl. D58—11)

FIG. 1 is a perspective view of a condiment container showing our new design;

FIG. 2 is a top plan view thereof; and

FIG. 3 is a side elevational view thereof.

The side not shown is substantially the same as the side shown.

The characteristic feature of my design for the condiment container disclosed resides in the tab portion thereof having the configuration as shown.

We claim:

The ornamental design for a condiment container, as shown and described.
